ATTORNEY

UNITED STATES PATENT OFFICE.

LINCOLN KUENEMANN, OF RAMAPO, ASSIGNOR TO WILLIAM I. WALTER, OF NEW YORK, N. Y.

DESIGN FOR A PATTERN FOR PRINTED FABRICS.

SPECIFICATION forming part of Design No. 24,095, dated March 12, 1895.

Application filed January 9, 1895. Serial No. 534,387. Term of patent 3½ years.

To all whom it may concern:

Be it known that I, LINCOLN KUENEMANN, a subject of the Queen of Great Britain, residing at Ramapo, in the county of Rockland 5 and State of New York, have invented and produced a new and original Design for a Pattern for Printed Fabrics, (Case D,) of which the following is a specification.

The leading features of my design consist 10 in the heavy unbroken bars having diamond shaped figures and dots thereon, and the intervening rows of superposed dots.

In the drawing forming part of this specification, the design for the pattern is shown 15 consisting of a series of heavy, contrasting

and parallel bars, within which are a series of intersecting diamond shaped figures and a dot between the apices of said figures, and between the bars is a row of small dots.

I claim—

The design for a pattern for a printed fabric, substantially as herein shown and described.

Signed in the city, county, and State of New York, this 3d day of January, 1895.

LINCOLN KUENEMANN.
